T. KLÖTZLI

ELECTRICAL CONNECTOR WITH AUTOMATIC CIRCUIT BREAKER

Filed March 29, 1923

Inventor:
Theodor Klotzli
By Alfred L.
A. L.

UNITED STATES PATENT OFFICE.

THEODOR KLÖTZLI, OF THOUNE, SWITZERLAND.

ELECTRICAL CONNECTER WITH AUTOMATIC CIRCUIT BREAKER.

Application filed March 29, 1923, Serial No. 628,436, and in Switzerland July 3, 1922.

My invention relates to an electrical connector having an automatic circuit-breaker of the kind comprising a wheel rigidly connected by a congealed fusible mass with a fixed part that is thermally connected with a circuit-closing member and serves to hold the spring-controlled circuit-closing contact-piece in its closed position by means of a pawl.

10 In apparatus of this kind known heretofore the circuit is opened always at the same temperature, and this invention has for its object a construction in which the circuit-breaker can be regulated for varying the 15 time at which it will operate.

To this end, in apparatus of the kind referred to, according to this invention, the tension of the spring controlling the circuit-closing contact-piece can be varied.

20 The invention consists in the construction, arrangement and combination of parts described hereinafter and pointed out in the claims.

An embodiment of the invention is illustrated by way of example in the accompanying 25 drawing, wherein:—

Figures 1 and 2 are elevations of the circuit-breaker in two different positions.

Figure 3 is a central vertical section 30 through Figure 1, and

Figure 4 is a detail.

In the construction of the connector as shown the two part casing 31, 32 is made of insulating material. In the part 32 is inserted a socket 33 having a longitudinal slit and a set-screw 34 for clamping the socket on a pin. The socket has at its upper end a lug 35 into which is screwed one end of a pivot-pin 36 whose other end is in the form of a cylindrical head 37 having a conical shoulder 38.

The pivot-pin 36 carries an annular casing 39 which has a ring of ratchet teeth 40 on its periphery constituting a ratchet wheel, the casing 39 being closed on the side overhanging the head 37 by a screw-threaded disc 41. The head 37 has a diametral slot 42, and the disc 41 has in its inner face two recesses 43. Between the end face of the head 37 and the disc 41 there is a space which is filled with a fusible mass 44 which, when cold, rigidly connects the parts 36, 37 with the parts 39, 40, 41.

At the rear of the wheel 40, that is at the 55 side thereof remote from the disc 41, a contact-arm 45 is rotatably mounted on the cas-

ing 39. This arm carries a three-armed pawl 47, 48, 49 rotatable about a screw 46 screwed into an extension 45' of the arm 45 on the opposite side of its axis of rotation, 60 which pawl is held in engagement with the toothed wheel 40 by a spring 50.

The contact-arm 45 is under the control of a coil spring 51 that surrounds the pivot-pin 36 and has its one end hooked into the head of a screw 52. This screw is screwed into a threaded socket 53 that extends through a hole 54 in the part 32 of the casing into the interior of the latter. By turning the socket 53 the tension of the spring 51 can be 65 regulated for causing the casing 39 with its contact-arm 45 to start rotating sooner or later and thereby varying the time when the circuit-breaker operates.

The contact-arm 45 cooperates with and 70 makes and breaks the circuit at a contact-piece in the form of a rectangular socket 55 (Figure 4) which is provided with a lateral lug 56 for engaging the arm 45, and has a hole 57 and a set-screw 58 for connection to 75 an electric conductor. For protecting the conductor immediately above the casing 31, 32, the latter has a screw-threaded hole 59 into which is screwed the one end of a closely coiled spring 60 (Fig. 1) the turns of which 80 are drawn apart in the hole 59 by the threads, whereby the spring is securely held 85 in the casing.

A switch lever 61 is rotatable on the casing 39 in front of the ratchet wheel 40. 90 This lever extends through the part 31 of the casing 31, 32 and carries on its outer end a knob 62. In order that the lever 61 shall not be exposed at all parts of its travel between its two limits of movement, the two 95 parts 31, 32 of the casing have each an arcuate bulged portion, as shown at 63.

The switch lever 61 has two rearwardly directed bent-over lugs 64, 65 extending 100 across the toothed wheel 40. The lug 64 contacts with the contact arm 45 and therefore as the lever 61 is rocked downwards moves the arm 45 against the action of the spring 51 until it is held under the lug 56 of the contact piece 55. In this position the contact arm is held by the pawl 47 engaging in the ratchet teeth 40 (Fig. 2). The lug 65 serves for releasing the pawl 47 from the ratchet teeth 40 by hand in order to be able 105 to break the circuit at will. When the switch lever 61 is rocked upwards, it presses the lug 65 inwards against the arm 48,

whereby the pawl 47 is disengaged from the ratchet wheel 40. The arm 49 slides along a cam face 66 which is in part concentric with the axis of the pivot-pin 36 and is situated on a shoulder 67 of the socket 33. In the circuit-closing position of the contact arm 45 (Fig. 2), the arm 49 extends to the left beyond the face 66, so that the pawl 47 can engage with the ratchet wheel 40, which is not possible when the arm 49 bears on the face 66 (Figure 1) so that the arm 45 does not make the circuit. Screw plugs 68 and 69 of insulating material are provided for closing the holes containing the socket 53 and the screw 58.

The switch can be closed and opened with one and the same lever by rocking it from its upper into its lower end position and reversely from its lower into its upper end position. The circuit is broken automatically by the action of the spring 51 on the contact arm 45, so that the latter is turned with the ratchet wheel 40 about the pivot-pin 36, 37 when the fusible material 44 becomes sufficiently heated to lose its rigidity. The circuit is broken instantaneously, the formation of an arc is prevented, so that the device can be used both for direct and alternating current.

30 I claim:—

1. In an automatic circuit-breaker, the combination of a fixed contact-piece, a pivot-pin, a ratchet wheel rotatable about said pin, a fusible mass normally rigidly connecting said wheel with said pin, a movable contact-piece arranged to make and break contact with said fixed contact-piece, one of the said contact-pieces being thermally connected with said pin, a pawl operatively connected with said movable contact-piece and arranged to engage with said wheel and hold the said movable contact-piece in contact with said fixed contact-piece, a spring operatively connected to said movable contact-piece and tending to move the latter into its circuit-breaking position, manually adjustable means for regulating the tension of said spring, and manually operable means for disengaging said pawl from said wheel.

2. In an automatic circuit-breaker, the combination of a fixed contact-piece, a pivot pin, a ratchet wheel rotatable about said pin, a fusible mass normally rigidly connecting said wheel with said pin, a movable contact-piece arranged to cooperate with said fixed contact-piece, one of the said contact-pieces being thermally connected with said pin, a spring operatively connected to said movable contact-piece and tending to move the latter into its circuit-breaking position, means for adjusting the tension of said spring, a pawl operatively connected with

said movable contact-piece and arranged to engage said wheel and hold the said movable contact-piece in contact with said fixed contact-piece against the action of said spring, and manually operable means for shifting said movable contact-piece in relation to said fixed contact-piece and simultaneously shifting said pawl in relation to said wheel.

3. In an automatic circuit-breaker, the combination of a fixed contact-piece, a pivot-pin, a ratchet wheel rotatable about said pin and forming therewith a chamber, a fusible mass in said chamber normally rigidly connecting said wheel with said pin, a movable contact-piece in the form of a lever mounted to rock about said pin, which lever has a contact-arm arranged to cooperate with said fixed contact-piece, a pawl mounted on said lever and engaging with said wheel, a spring coiled about said pin and operatively connected to said contact-arm and tending to move the latter into its circuit-breaking position against the action of said pawl, and a switch lever mounted to rock about said pin, the said switch lever having an arm adapted to coact with said contact-arm and move the same against said fixed contact-piece, when the switch lever is rocked in one direction, and a second arm adapted to coact with said pawl and disengage the same from said wheel, when said switch lever is rocked in the other direction.

4. In an automatic circuit-breaker, the combination of a fixed contact-piece, a pivot-pin, a ratchet wheel rotatable about said pin and forming therewith a chamber, a fusible mass in said chamber normally rigidly connecting said wheel with said pin, a movable contact in the form of a lever mounted to rock about said pin, which lever has at one side of said pin a contact-arm arranged to cooperate with said fixed contact-piece, a spring coiled about said pin and operatively connected to said contact-arm and tending to move the latter into its circuit-breaking position, a tail piece, a pawl mounted on said tailpiece and engaging with said wheel for holding said lever against the action of said spring, the said pawl having two lugs, a switch lever mounted to rock about said pin, and having one arm for coacting with said contact-arm to move it against the action of said spring, and a second arm adapted to coact with one of said lugs to disengage said pawl from said wheel, and a cam arranged to coact with the second of said lugs and hold the pawl disengaged from said wheel, when the contact-arm is in its circuit-breaking position.

In testimony whereof, I affix my signature.

THEODOR KLÖTZLI.
